Primary Examiner — Robert M Spear*Assistant Examiner* — Ryan Harvey*(74) Attorney, Agent, or Firm* — Saul Ewing LLP(57) **CLAIM**

The design for a wall mountable bicycle stand, as shown and described.

DESCRIPTION

FIG. 1 is a front perspective view of a wall mountable bicycle stand;

FIG. 2 is a front view thereof;

FIG. 3 is a back view thereof;

FIG. 4 is a left view thereof;

FIG. 5 is a top view thereof;

FIG. 6 is a bottom view thereof; and,

FIG. 7 is an open front view thereof.

The broken lines illustrate portions of the article that form no part of the claimed design.
